Patented Dec. 3, 1912.

UNITED STATES PATENT OFFICE.

CARL F. SCHULZ, OF BROOKLYN, NEW YORK.

CARBURETER.

1,046,111.

Specification of Letters Patent.

Patented Dec. 3, 1912.

Application filed August 21, 1911. Serial No. 645,099.

To all whom it may concern:

Be it known that I, CARL F. SCHULZ, citizen of the United States, residing at Brooklyn, in the county of Kings and State of New York, have invented certain new and useful Improvements in Carbureters, of which the following is a specification.

This invention comprehends certain new and useful improvements in carbureters for internal combustion engines and relates particularly to that type of carbureter in which the air and fuel valves are simultaneously operated through the instrumentality of a lever fulcrumed intermediate of its ends within the carbureter casing.

The present invention has for its primary object an improved construction of carbureter of this character embodying means whereby the fulcrum point of said lever may be shifted or adjusted in two dimensions so that such point may be varied, within certain limits in any direction or to any desired position, while at the same time, no matter what the adjustment may be, the fulcrum point is always in line with the pivots at the extremities of the lever.

The invention has for a further object mechanism of the character indicated in the preceding paragraph, so constructed and arranged that the two adjustments of the fulcrum point, that is, the adjustment toward and from either pivot point and in a direction substantially at right angles thereto, are absolutely independent of each other.

The invention also has for an object mechanism of this character and for this purpose which is so constructed and arranged that the fulcrum point will be held in its adjusted position without any independent locking mechanism. And the invention further aims to generally improve this class of devices and to simplify them and to render them more useful and commercially desirable.

With these and other objects in view as will more fully appear as the description proceeds, the invention consists in certain constructions, arrangements and combinations of the parts that I shall hereinafter fully describe and claim.

For a full understanding of the invention, reference is to be had to the following description and accompanying drawings, in which:

Figure 1 is a side elevation of a carbureter constructed in accordance with my invention; Fig. 2 is a vertical sectional view

thereof; Fig. 3 is a detail perspective view of one of the actuating screws; and, Fig. 4 is a similar view of a fulcrum carrying plate hereinafter specifically described.

Corresponding and like parts are referred to in the following description and indicated in all the views of the drawings by the same reference characters.

Referring to the drawing, the numeral 1 designates the casing of my improved carbureter, 2 the mixture passage therein, 3 the inspirator nozzle or fuel valve mounted in the primary portion of the mixture passage, and 4 an air admission valve, the latter being provided with a rod 5 movable within a cylinder 6 in which a suspension spring 7 is mounted, said spring being so connected to the rod 5 as to normally hold the air admission valve at the upper limit of its movement, closing the air admission ports 8.

A lever 9 is pivotally connected at its ends to the fuel valve 3 and air valve 4, said lever being fulcrumed intermediate of its ends on a shiftable fulcrum 10 which in the present instance is in the form of a pin projecting laterally from the inner face of a plate 11 which is disposed on the outer side of the casing 1 and which lies with a snug fit over and upon an opening 12, of predetermined size, formed in the side wall of the casing 1 and communicating with the air passage 2.

A bell crank lever 13 is fulcrumed at its elbow, as at 14, on the outer side of the casing 1, the fulcrum point of said bell crank being coincident with the point of pivotal connection between the lever 9 and the air valve 4 when the latter is in closed position; but it is to be understood that the said fulcrum and pivot point are entirely independent of each other. One arm of the lever 13, said arm being designated 15, is formed with a stem 16 on which a screw 17 is swiveled, being detachably held thereon by a nut, as shown, and said screw works through a threaded bore 18 which is formed in the plate 11, whereby the turning of the screw will effect the movement of the plate 11 longitudinally of said arm 15 and result in the desired adjustment of the fulcrum pin 10 of the lever 9 in one dimension.

The arm 15^a of the bell crank 13 is mounted between and in engagement with shoulders 19, that are formed on an adjustment screw 20 which works within a threaded bearing 21 formed on the casing 1, so that by turning the screw 20, the bell crank 13

may be rocked and the fulcrum pin 10 adjusted as desired in the other dimension. Thus it will be seen that the fulcrum of the lever 9 may be shifted as desired, the two 5 adjustments being entirely independent of each other and the fulcrum remaining in adjusted position without the necessity of employing separate locking means therefor. It will also be seen that, whatever the adjustment, the fulcrum is always in line with the pivots at the extremities of the lever 9. In the present embodiment of the device, the lever 9 shifts with its fulcrum, the ends of said lever being inserted underneath and in 10 engagement with rollers that are carried by pivot pins 22 and 23, carried by the air admission valve 4 and fuel valve 3, respectively. Preferably, a leaf spring 24 is secured to the underside of the lever 9, the two free ends of said spring serving to 15 maintain the lever always in contact with the pivots and for taking up wear.

25 designates a finger which is in the present instance secured to the bearing 21 and which presses against the plate 11 so as to hold the same against the opening 12 so as to avoid air leakage.

From the foregoing description in connection with the accompanying drawing, the 30 operation of my improved carbureter and particularly the fulcrum point adjusting means, will be apparent, the same having been described in connection with the construction and relative arrangement of parts.

35 It is to be understood that while the accompanying drawing shows what I believe to be the preferred embodiment of my invention, the invention is not necessarily limited thereto as various changes may be 40 made in the construction, arrangement and proportions of the parts without departing from the scope of the invention as defined in the amended claims.

Having thus described the invention, what 45 is claimed as new is:

1. A carbureter including an air valve, a fuel valve, and a lever operatively connected to said valves and having its fulcrum relatively fixed with relation to the lever, 50 said fulcrum and lever being shiftable in two dimensions.

2. A carbureter embodying an air valve, a fuel valve, and a lever operatively connected to said valves and having a relative fixed 55 fulcrum, said fulcrum and lever being shiftable with its fulcrum in two dimensions.

3. A carbureter including an air valve, a fuel valve, a lever operatively connected to said valves and fulcrumed intermediate of 60 its ends, the fulcrum of said lever being relatively fixed and means for moving the lever and fulcrum point in two dimensions and holding the same in adjusted position.

4. A carbureter including a casing, an air 65 valve and a fuel valve in said casing, a lever

interposed between said valves and fulcrumed intermediate of its ends, said fulcrum having a fixed relation to the lever, and means located on the outside of the casing for moving the fulcrum point and said lever in two dimensions. 70

5. A carbureter, including an air valve, a fuel valve, a lever fulcrumed intermediate of its ends and operatively connected to said valves, a plate to which the fulcrum of said lever is connected, a lever on which said plate is longitudinally adjusted, and means for moving said last named lever. 75

6. A carbureter, including an air valve, a fuel valve, a casing in which the same are mounted, the casing being formed with an opening, a plate disposed against the casing at said opening and provided with a fulcrum pin, a lever fulcrumed intermediate of its ends on said pin, and operatively connected to said valves, a bell crank fulcrumed on the casing, said plate being longitudinally adjustable on one arm of said bell crank, and means connected to the other arm of said bell crank for shifting the 90 latter. 80

7. A carbureter including an air valve, a fuel valve, a casing in which said valves are mounted, the casing being formed with an opening, a plate applied to the side of the 95 carbureter casing at said opening, a bell crank fulcrumed on said casing, an adjustment screw swiveled on one arm of said bell crank and working in said plate, an adjustment screw mounted on the casing and operatively engaging the other arm of said bell crank, the plate being provided with a fulcrum pin extending into the carbureter casing through said opening, and a lever fulcrumed on said pin and operatively connected to said valves. 100 105

8. A carbureter including a casing, provided with an air passage, air and fuel valves mounted in said casing, the casing being formed with an opening entering said passage, a plate applied to the carbureter casing over said opening and formed with a screw threaded bore, a bell crank fulcrumed on the casing, an adjustment screw swiveled on one arm of said bell crank and working in the 110 threaded bore of said plate, another adjustment screw working on the casing and operatively engaging the other arm of said bell crank, and a finger carried by the casing and pressing against said plate to hold it in close engagement over said opening. 115 120

9. A carbureter, including an air valve, a fuel valve, a casing in which the same are mounted, the casing being formed with an opening, a plate disposed against the casing 125 at said opening and provided with a fulcrum pin, a lever fulcrumed intermediate of its end on said pin and operatively connected to said valves, the fulcrum pin of said lever being always maintained sub- 130

- stantially in alignment with the pivot points between said lever and said valves, a bell-crank fulcrumed on the casing, said plate being longitudinally adjustable on one arm 5 of said bell-crank, and means connected to the other arm of said bell-crank for shifting the latter.
10. A carbureter, including a casing formed with a primary air passage, a fuel valve mounted in said passage, the casing being formed with ports distinct from said primary air passage, an air admission valve mounted in the casing and controlling said ports, a lever mounted in the casing and 15 operatively connected to the fuel valve and air admission valve, said lever having a fulcrum relatively fixed in relation to the lever and supporting the lever intermediate of its ends, said lever and its fulcrum being shift- 20 able in two dimensions.
11. A carbureter, including a casing, fuel and air admission valves mounted therein, a lever mounted in the casing and operatively connected to said valves, a plate provided 25 with a fulcrum pin on which said lever is mounted intermediate of its ends, the casing being formed with an opening receiving said pin, a bell-crank fulcrumed on the casing at a point co-incident with the pivot point be- 30 tween the lever and air admission valve in the closed position of the latter, said bell-crank fulcrum and said pivot point being independent of each other, the plate being longitudinally adjustable on one arm of said 35 bell-crank, and means connected to the other arm of said bell-crank for shifting the latter.
12. A carbureter, including a casing, fuel and air admission valves mounted therein, a lever pivotally connected to said valves and 40 mounted in the casing, a plate provided with
- a fulcrum pin on which said lever is fulcrumed intermediate of its ends, the casing being formed with an opening receiving said pin, a bell-crank fulcrumed to turn about a 45 fixed axis on the casing, the plate being longitudinally adjustable on one arm of said bell-crank, and means connected to the other arm of said bell-crank for shifting the latter. 50
13. A carbureter, including an air valve, a fuel valve, a lever interposed between the two valves and having a longitudinally movable operative connection therewith, said lever being fulcrumed intermediate of 55 its ends, the fulcrum point being fixed with relation to the lever, and means for shifting the lever and its fulcrum point in two dimensions.
14. A carbureter including an air valve 60 and a fuel valve, a lever operatively connected to said valves and having a fulcrum fixed with relation to the ends of the lever, a movable plate to which the fulcrum of said lever is connected and by which the 65 lever is supported, and means for moving said plate into any position in the same plane.
15. A carbureter including an air valve, a fuel valve, a lever operatively connected 70 to said valves and having a relatively fixed fulcrum, a movable plate to which the fulcrum of said lever is connected and whereby the fulcrum and the lever may be longitudinally shifted and a lever operatively con- 75 nected to the plate for shifting the same.

In testimony whereof I affix my signature in presence of two witnesses.
